UNITED STATES PATENT OFFICE.

DOUGLAS L. SAUERHERING, OF WAUSAU, WISCONSIN.

POWER-TAMP.

1,235,729.

Specification of Letters Patent.

Patented Aug. 7, 1917.

Application filed August 28, 1916. Serial No. 117,294.

To all whom it may concern:

Be it known that I, DOUGLAS L. SAUERHERING, a citizen of the United States, residing at Wausau, in the county of Marathon 5 and State of Wisconsin, have invented certain new and useful Improvements in Power-Tamps; and I do declare the following to be a full, clear, and exact description of the invention, such as will enable others skilled in the art to which it appertains to 10 make and use the same.

My invention aims to provide a comparatively simple yet highly efficient machine designed primarily for tamping ensilage in 15 silos as it is deposited therein by the usual pneumatic conveyer, although it will be understood that the device can well be used for other purposes, such as for packing roadways, tennis courts, etc.

With the foregoing in view, the invention resides in certain novel features of construction and in unique combinations of parts to be hereinafter fully described and claimed, the descriptive matter being supplemented 20 by the accompanying drawings which constitute a part of this application and in which:

Figure 1 is a vertical section of a silo showing the device suspended for operation 30 therein;

Fig. 2 is an enlarged side elevation of the machine;

Fig. 3 is a top plan view thereof;

Fig. 4 is an end elevation;

Fig. 5 is a vertical transverse section taken on the plane of the line 5—5 of Fig. 2.

Throughout the several views of the drawings above briefly described, similar characters designate corresponding parts. The 40 numeral 1 has reference to a rectangular frame disposed in a horizontal plane, said frame having bearings 2 on its opposite ends in which a central shaft 3 is revolvably mounted, said shaft being driven from an 45 electric motor 4 which is mounted on the frame. Motion may be imparted to the shaft 3 in one direction by means of intermeshing gears 5 on said shaft and the shaft of the motor, when a clutch member 6 is 50 moved in one direction by means of a hand lever 7, or when said member is shifted in the opposite direction, the direction of rotation of the shaft 3 will be reversed since it is then driven by means of sprockets 8 and 55 a sprocket chain 9. The frame 1 is provided with a U-shaped handle 10 to be

grasped by the operator in the manner hereinafter explained.

U-shaped hangers 11 are secured at their upper ends to the ends of the frame 1 and at 60 their lower ends are provided with vertically adjustable shoes 12 adapted to travel over the ensilage being packed. A crank shaft 13 is revolvably mounted in suitable bearings carried by the lower ends of the 65 hangers 11, said shaft being driven from the shaft 3 by means of sprockets 14 and a chain 15, said shaft 13 preferably rotating at one-half the speed of the shaft 3.

Two or more tamp bars 16 have bearings 70 near their lower ends mounted on the opposed cranks 17 of shaft 13 and the upper ends of said bars are formed with longitudinal slots 18 through which the shaft 3 passes, collars 19 being secured on said shaft 3 adjacent the opposite sides of the bars 16 to guide the latter in their vertical movements. The lower ends of the bars 16 are provided with flat tamping feet 20 preferably pivoted thereto. 75

A disk or the like 21 is secured on one end of the shaft 3 and said disk carries a wrist pin 22 thus forming in effect a crank or eccentric, said pin being passed through the upper end of a link 23 whose lower end is 80 pivoted to a vertical tamp bar 24 mounted slidably in a guide 25 secured to one of the hangers 11. The lower end of the bar 24 is provided with a tamping foot 26 preferably of less size than the feet 20 but mounted 85 in the same manner.

A bail 27 is pivotally connected with and rises from the frame 1, it being to this bail that the lower end of a suspending cable 28 is secured. When the machine is to be used 90 in a silo, the cable 28 is passed over pulleys 29 and 30 secured in the upper end thereof and is provided on its free end with a weight 31 disposed on the exterior of the silo, said weight approximately balancing 100 the machine so that it will be sustained in a vertical position but may be moved in any required manner over the ensilage being packed. A hood 32 is by preference secured on the cable 28 above the machine so that the operator who grasps the handle 10 to manipulate the machine will be shielded 105 from the falling ensilage conveyed to the upper end of the silo by the usual pneumatic or other type of conveyer. This type of conveyer will in most cases be provided with an electric generator for supplying current to 110

the motor 4, this current being led through suitable wires.

The motor 4 is made to drive the shaft 3 in one direction or the other by proper manipulation of the lever 7 and said shaft in turn imparts rotary motion to the crank shaft 13. The throw of the cranks 17 now causes the bars 16 and the feet 20 thereof to reciprocate and at the same time oscillate and this motion causes the entire machine to move over the surface being tamped, the operation being very similar to that of a person walking. The feet 20 thus effectively pack the material and all that is required of the operator is that he guide the machine since it will feed itself forwardly or rearwardly according to the position of the lever 7, the foot 26 being adapted to pack the material along the wall of the silo which is not accessible to the other feet.

I claim:—

1. A power tamp comprising a frame, a plurality of tamping members carried thereby and means for moving said members upwardly and downwardly and at the same time forwardly and rearwardly in respect to the frame, whereby the machine is caused to travel over the material being tamped.

2. A power tamp comprising a plurality of vertically disposed tamping bars mounted adjacent their upper ends for simultaneous reciprocation and oscillation, and means for reciprocating said bars vertically and at the same time oscillating them to move the lower ends thereof forwardly and rearwardly.

3. A power tamp comprising a plurality of vertically disposed tamping bars mounted adjacent their upper ends for simultaneous reciprocation and oscillation, said bars having bearings, and a driving shaft having cranks mounted in said bearings to reciprocate and at the same time oscillate said bars to move their lower ends forwardly and rearwardly.

4. A power tamp comprising upper and lower shafts, the latter having cranks and the upper having collars disposed in vertical alinement with said cranks, means for driving the lower shaft, and a plurality of

tamp bars having slotted upper ends through which the upper shaft passes and against which the collars bear, said bars also having bearings receiving the cranks of the lower shaft.

55

5. A power tamp comprising upper and lower shafts, the lower shaft having cranks and the upper one having collars disposed in vertical alinement with said cranks, means for driving the two shafts, a plurality of tamp bars having slotted upper ends through which the upper shaft passes and against which the collars thereof bear, said bars also having bearings receiving the cranks of the lower shaft, another crank 60 on one end of the upper shaft, and an additional tamp bar having connection with said crank.

60

6. A power tamp comprising a horizontally disposed rectangular frame, a pair of 70 U-shaped hangers depending from the ends of said frame and having bearings at their lower ends, a driven shaft rotatably mounted in said bearings and having cranks, a plurality of vertically disposed tamp bars 75 having bearings receiving said cranks, and means for guiding the upper ends of said bars.

75

7. A power tamp comprising a horizontally disposed rectangular frame, a pair of 80 U-shaped hangers depending from the ends thereof and having bearings at their lower ends, a shaft rotatably mounted in said bearings and having cranks, another shaft rotatably mounted on the frame and having 85 a crank at one end, means for driving the two cranks, a plurality of vertically disposed tamping bars having bearings receiving the cranks of the first named shaft, said bars also having slots through which the 90 second shaft passes, and an additional tamp bar having connection with the crank of the last named shaft.

85

In testimony whereof I have hereunto set my hand in the presence of two subscribing 95 witnesses.

DOUGLAS L. SAUERHERING.
